(57) **CLAIM**

The ornamental design for a holster blank and holster design, as shown and described.

DESCRIPTION

FIG. 1 is a top, front perspective view of the outside of the holster blank;

FIG. 2 is a bottom front perspective view of the inside of the holster blank;

FIG. 3 is a bottom front perspective view of FIG. 2 rotated 180°;

FIG. 4 is a top, rear perspective view of the outside of FIG. 1 at another angle;

FIG. 5 is a top plan view of FIG. 1;

FIG. 6 is a bottom plan view of FIG. 1;

FIG. 7 is a left side elevational view of FIG. 5;

FIG. 8 is a rear side elevational view of FIG. 5;

FIG. 9 is a top muzzle and outer side perspective of the holster body formed by folding the holster blank of FIG. 5 which contacts the two clam-like halves together;

FIG. 10 is a top muzzle and inner side perspective of the holster body of FIG. 10;

FIG. 11 is a side elevational view of FIG. 11;

FIG. 12 is a side elevational view of FIG. 10;

FIG. 13 is a top plan view thereof FIGS. 10 and 11;

FIG. 14 is a bottom plan view of FIGS. 10 and 11;

FIG. 15 is a front end elevational view of FIGS. 10 and 11; and,

FIG. 16 is a rear end elevational view of FIGS. 10 and 11.
